(57) **CLAIM**

The ornamental design for a storage box as shown and described.

DESCRIPTION

FIG. 1 is a front top left perspective view showing the storage box.

FIG. 2 is an enlarged view of the circled area 2 of FIG. 1 showing the details of the raised features within the circled area. These raised features on the front of the storage box are consistent with the raised features shown on the top of the storage box.

FIG. 3 is a rear right top perspective view showing the storage box of FIG. 1.

FIG. 4 is a rear right bottom perspective view showing the storage box of FIG. 1.

FIG. 5 is a front elevation view of the storage box of FIG. 1.

FIG. 6 is a back elevation view of the storage box of FIG. 1.

FIG. 7 is a left end elevation view of the storage box of FIG. 1.

FIG. 8 is a right end elevation view of the storage box of FIG. 1; FIG. 8 is a mirror image of FIG. 7.

FIG. 9 is a top view of the storage box of FIG. 1.

FIG. 10 is a bottom view of the storage box of FIG. 1. The broken lines in FIGS. 1 and 2 illustrate the bounds of the enlarged view and form no part of the claimed design.
